DRYING MACHINE

Filed Oct. 21, 1922

INVENTOR:
Pascal J. Shampay
By Nissen & Crane
ATTYS.

UNITED STATES PATENT OFFICE.

PASCAL J. SHAMPAY, OF CHICAGO, ILLINOIS.

DRYING MACHINE.

Application filed October 21, 1922. Serial No. 595,952.

To all whom it may concern:

Be it known that I, PASCAL J. SHAMPAY, a citizen of the United States, residing at Chicago, in the county of Cook and State 5 of Illinois, have invented certain new and useful Improvements in Drying Machines, of which the following is a specification.

My invention relates to drying apparatus particularly adaptable for drying blankets, 10 and the like. One of the objects of the invention is the provision of simple and efficient drying mechanism adapted to dry blankets, and the like, in tubular form.

A further object is the provision of a 15 tubular drying drum adapted for movement to convenient position for attaching a blanket, or the like.

A further object is the provision of a 20 drying means such as referred to having means for holding parts of a blanket in position while the rest of the blanket is being placed on the drier.

A further object is the provision of a 25 tubular drying device disposed in vertical condition when in use and adapted for swinging to horizontal position for attaching the goods to be dried.

A still further object is the provision of 30 drying mechanism adapted to hold a blanket in stretched condition during drying.

Other objects will appear hereinafter.

An embodiment of my improvement is 35 illustrated in the accompanying drawing, forming a part of this specification, and in which—

Fig. 1 is a vertical section of drying mechanism embodying my invention; and

Figs. 2 and 3 are horizontal sections taken on lines 2—2 and 3—3, respectively, of 40 Fig. 1.

Referring more particularly to the drawing, I have indicated a hollow base 4 having its top opening 5 substantially cylindrical and opening upwardly. In the upper 45 portion of the base 4 adjacent the opening 5 is a heater 6 which in the present instance is indicated as being a coiled steam pipe, or the like, but it will be understood that any desired form of heating means may be provided.

At a suitable portion of the base 4 is an opening 7 in which is mounted a fan 8 operated by a motor 9. The fan 8 and motor 9 may be any desired means for forcing

a current of air through opening 7 into the 55 hollow base 4 so that air can be forced up around and through the heater 6 and out through the opening 5.

Lying on the top of the base 4 is a circular member or spider 10 hinged as at 11 60 to one side of the base 4, as clearly indicated in Fig. 1. The spider 10 has a central hub 12 in which is journaled the lower end of a shaft 13. The shaft 13 may be held by collars 14 or any other desired means 65 for preventing longitudinal movements of the shaft in said hub 12. Fixed on the shaft 13 just above spider 10 is the hub 15 of a wheel 16, the outer periphery of which is substantially of a size of the base 4 and 70 spider 10. Extending upwardly and attached to the wheel 16 is a cylinder 17 which is of a porous or foraminous material, such as wire gauze, or the like, so that the air passing through opening 5 may 75 pass out through the openings of said cylinder 17. Telescoping in the upper end of cylinder 17 is another cylinder 18 which is of like material and adapted for the passage of the heated air in the same manner 80 as cylinder 17. The upper end of cylinder 18 is attached to a solid disc 19 which has a hub 20 splined on the upper end of shaft 13.

A key 21 may be used for splining the 85 hub 20 on shaft 13. This key may be provided with notches 22 which are adapted to engage a dog 23 mounted in an extension 24 of the hub 20. The cylinders 17 and 18 are therefore held against relative rotary 90 movements and mounted so that they can be telescoped as indicated to accommodate different lengths of blankets or other goods to be dried. It will be understood that the locking means 21, 22 and 23 may be of 95 any desired form so as to hold the cylinders 17 and 18 in desired relative positions.

The tubes 17 and 18 are preferably arranged with their axis vertical so that the heated air will have a tendency to pass out 100 of all of the openings in said cylinders evenly. This will insure the even drying of the blankets, and the like.

On the peripheries of wheel 16 and disc 19 are a plurality of points 25 upon which 105 the edges of the blanket or other article to be dried may be fastened to hold such blanket, or the like, in condition for forcing the

air out through the pores thereof for drying such blanket.

It is convenient in attaching a blanket, or the like, to have the drying apparatus move to a horizontal position, such as indicated in dotted lines in Fig. 1. When in this position an operator can start one edge of the blanket or other article to be dried on an upper portion of the cylindrical drying device and then by turning such device on the shaft 13 easily fix the blanket on said drying drum. Sometimes a portion of the blanket on the lower side of the drum tends to fall off of the points 25 before the blanket is entirely fastened in place. In such cases I provide semi-cylindrical guards 26 and 27. The guard 26 is preferably journaled as at 28 on the extension 24 so that when the device is in the dotted line position gravity 20 will maintain the guard 26 in the position indicated by dotted lines in Fig. 1. The ledge will insure holding the blanket on said pins. The guard 27 is attached to the member 10 and does not rotate but is held in such 25 position by being rigidly attached to said member 10. The members 26 and 27 further have the function of preventing the operator's clothes from getting caught on the pins 25.

30 A leg 29 may be pivoted as at 30 on the upper end of shaft 13 so as to help support the drying drum in the dotted line position of Fig. 1 and prevent binding of the parts. The leg 29 is indicated as having a hinge 31 35 in it so that a portion drops downwardly in the full line position shown in Fig. 1. This portion 32 may provide a means for the operator to grasp in swinging the drum on its hinge 11 from the full line to the dotted line 40 position of Fig. 1. The leg 29 should be journaled on shaft 30 so that the drum can be rotated easily with shaft 13. The shaft should also rotate as above indicated so that the pins in wheel 16 cannot rotate with relation to pins in disc 19, thereby twisting the 45 blanket.

The blanket may be attached to the pins 25 in a rather loose condition with respect to the distance between the pins at one end 50 and the pins at the other end of the drum. Then after the blanket is attached to said pins the operator grasps handles 33 and pulls the disc 19 out toward leg 29. The locking means 22-23 is such that it will 55 hold the blanket in this stretched-out condition. When it is desired to remove the blanket it is only necessary to swing member 23 to free it from the notches 22 to let a blanket free so that it may be easily removed from the pins 25.

When the drum is in its dotted line position of Fig. 1 it is preferably of a height so that an operator may easily place a blanket on the drum in much the same way as if he 65 were securing the blanket to a table. It will

also be noted that the air may be heated and forced into the end of the drum in any desired manner.

I claim:

1. A drier comprising a hollow base having an opening in one side; means connected with the base for moving air out of the latter through said opening; and a tubular blanket support hinged at one side to said base over said opening and adapted for 75 swinging away from such opening.

2. A drier comprising a hollow base having an opening in one side; means for moving air through said base from said opening; and a tubular blanket support attached 80 to said base over said opening.

3. A drier comprising a base having an air passage therethrough; and a tubular blanket support attached to said base, one end of said blanket support being open to receive air from said base and the other end of said blanket support being closed, the side walls of said blanket support having openings therein.

4. A drier comprising a hollow base having an opening in one side; two telescoping foraminous tubes positioned with the end of one of said tubes over said opening; a tight closure closing an end of the other of said tubes; and means for forcing air through 95 said base and out through the foraminous tubes.

5. A drier comprising a base having an air passage therethrough; a spider extending across said air passage; a shaft journaled 100 in said spider; a drying drum fixed on said shaft; and a hinge connecting the spider with said base and permitting the swinging of said drum away from said air passage.

6. A drier comprising a base having an 105 air passage therethrough; a spider attached to the base and disposed across said air passage; a shaft journaled in said spider; two telescoping tubes disposed around said shaft; a spider fixed on said shaft and attached to one end of one of said tubes; a disc splined on said shaft and attached to an end of the other tube; and means for adjusting the last-mentioned tube on the shaft with respect to the first-mentioned tube.

7. A drier comprising a hollow base with an air discharging opening in one side; a spider attached to said base and disposed across said air opening; a shaft journaled in said spider; a head fixed on said shaft adjacent said spider, there being air passages through said head; an imperforate head splined on said shaft; telescoping foraminous tubes attached to said heads and disposed around said shaft; and a locking means for locking the splined head at different positions along said shaft.

8. A drier comprising a member having an air passage therethrough; a spider disposed over said air opening and pivoted to 120

- 5 said base; a shaft journaled in said spider; a drum fixed on said shaft with one end of the drum open and adjacent said spider; and a leg journaled on said shaft adjacent 40
 5 said drum for supporting a part of said drum when the latter is in one of its positions.
9. A drier comprising a drying drum having two telescoping portions; means for 10 holding said telescoping portions against relative rotary movements; a lock for locking said telescoping portions against relative longitudinal movements; and means for forcing air through said drum.
- 15 10. A drier comprising a hollow base open at one side; means for moving hot air through said base and out of said opening; a tubular blanket drier open at one end with its open end disposed over the opening in 20 said base; points on said drum adjacent the ends thereof; and means for covering said points to facilitate holding an article to be dried on said points.
- 25 11. A drier comprising a hot air furnishing means; a tubular blanket drier having one end open and communicating with the hot air furnishing means, the other end of said blanket drier being closed; and means for guiding the movements of the blanket 30 drier away from and toward the hot air furnishing means.
- 35 12. A blanket drier comprising a drum having a plurality of telescoping tubular walls; a head in the remote end of one of said walls with openings in said head; warm air furnishing means connected with said 45 head; an imperforate head in the remote end of another tubular wall; and means for locking the tubular walls in different relative longitudinal movements. 50
13. A drier comprising a hollow base having an intake opening and a discharge opening; a tubular drier having an open end over the discharge opening; a fan connected to force air into the intake opening; a heater 45 in said base between said openings; and means for moving the drier away from said discharge opening.
14. A drier comprising a support; a spider hinged to said support; a drying tube journaled in said spider; pins at the ends of said drying tube; and shields at the ends of said drying tube covering certain of said points. 55
15. A drier comprising a support; a spider hinged to said support, a drying tube journaled in said spider; pins at the ends of said drying tube; shields at the ends of said drying tube covering certain of said points; and a leg pivoted to said drying tube and adapted to assist the base in supporting said drying tube in one position of the latter. 60
16. A drier comprising a drum having one end opened and the other end closed with the tubular walls of said drum having openings therein; and means for forcing air into the 65 open end of said drum toward the closed end of the latter and out through the openings of its curved walls.

In testimony whereof I have signed my name to this specification on this 19th day 70 of October, A. D. 1922.

PASCAL J. SHAMPAY.
